COMPRESSOR

Lindsay Hugh Browne, Rochester, N. Y., assignor
to Kellogg Manufacturing Co., Rochester, N. Y.,
a corporation of New York

Application October 4, 1932, Serial No. 636,214

7 Claims. (Cl. 230—172)

This invention relates to improvements in compressors and more particularly to the valve arrangement including the intake and exhaust valves of a compressor which is particularly adapted for use in a refrigerating system.

The primary object of the invention is the provision of a new and improved valve assembly for compressors.

Another and further object of the invention is the provision of a new and improved complete valve assembly which is quickly, easily and cheaply replaceable in the compressor as a complete unit.

Another object of the invention is the provision of improved valves for a complete valve assembly for compressors, the predominant features of which are the quiet action of the valves and the cover plates for the valves for limiting their movement and for catching and preventing any parts of the valves from dropping into the compressor cylinder in the event one of the valves is broken.

Many other specific novel features of construction and improved results will be pointed out and listed in the following description and will be treated in detail therein and understood fully when the description is read in the light of the accompanying drawings.

In the drawings:

Fig. 1 is a diagrammatic lay-out of a refrigerating system having therein the present compressor including the improved valve assembly therefor.

Fig. 2 is a vertical sectional view through the upper end of the compressor and the valve assembly therefor.

Fig. 3 is a bottom plan view of the valve plate which constitutes the valve assembly.

Fig. 4 is a vertical sectional view taken at right angles to Fig. 2 and on the line 4—4 of Fig. 2 looking in the direction indicated by arrows.

Fig. 5 is a sectional view through the discharge and suction shut-off valve.

Fig. 6 is a view in strung-out perspective of one of the valve cover plates and one of the valves used in conjunction therewith.

Having reference particularly to Figure 1, the refrigerating system will be described in broad terms as mechanical refrigerating systems are well understood and a detailed description of its parts and operation is not considered necessary.

A represents the compressor which is driven through a belt connection B with a combined electric motor and fan C. The condenser and receiver is indicated at D, the expansion valve at

E, the evaporator at F, a thermostat bulb and suction line clamp at G, and a thermostat at H. A suction controlled valve is positioned at K, a discharge control valve at L and the receiver shut-off valve at M.

It will be evident that the compressor is connected with the condenser and receiver by a pipe N, that the condenser and receiver is connected with the expansion valve by a pipe O which valve in turn is connected with the evaporator which has connection with the intake valve K of the compressor.

The thermostat bulb and thermostat G and H are for the purpose of opening and closing the electric circuit for stopping and starting the driving motor C to start and stop the refrigerating action of the system.

The compressor in most of its structure is of a more or less conventional form and in the drawings is illustrated as a single belt driven unit of the reciprocating type and comprises a crank case 1 having therein a crank shaft 2 to which is connected a piston connecting rod 3 for reciprocating the piston 4 in the cylinder 5, which cylinder is provided on its outer periphery with a series of extending fins 6 for radiation of heat which assists in keeping the cylinder cool.

It is of course intended that in the base or crank case 1 of the compressor oil is provided for the lubrication of the parts by the common splash system. The piston 4 is not provided with rings but is provided with two oil grooves 7. Rings for the piston are not considered necessary for proper compression as the clearance between the piston and the walls of the cylinder is something less than one-half of one thousandth of an inch.

The compressor is of course provided with a head which is designated as an entirety at 8 but between the cylinder head and the upper end of the cylinder is interposed a valve plate which carries the complete valve assembly, which plate is designated as an entirety by the numeral 9.

The suction intake of the compressor from the evaporator is designated at 10 and the compressor discharge to the condenser is indicated at 11. The outer ends of these passageways 10 and 11 in the outer face of the compressor are enlarged to provide seats 12 which are adapted to receive suitable fittings in which are the suction and discharge shut-off valves K and L respectively.

The compressor cylinder throughout its length is provided with a vertically arranged bore or passage 13, the lower end of which communicates with the crank case while its upper end is open. Intermediate its length this bore is joined by the

suction inlet passageway 10. A second vertically arranged bore 14 has its lower end communicating with the compressor discharge conduit or passageway 11 while its upper end is open.

5 It is upon the upper end of the compressor cylinder and over the open ends of the bores or passageways 13 and 14 that the valve plate 9 rests. In other words the valve plate which contains both the suction and discharge valves of the compressor lies in the head of the compressor.

10 Having particular reference to this valve plate 9 the construction of which is illustrated in Figures 2, 3, 4 and 6, it will be seen that the plate 9 itself is circular in shape to agree with the shape and configuration of the compressor cylinder and that it is secured in place between the compressor head 8 and the upper end 15 of the compressor cylinder by a plurality of bolts 16. The plate has in its under face a bore 17 adapted to receive the upwardly extending end of a dowel pin 18 positioned in the compressor head. This dowel pin properly locates the valve plate of the compressor head to prevent any error in assembly and also automatically aligns the bolt holes of the valve plate with 25 the bolt holes in the cylinder head and upper end of the cylinder.

15 The valve plate has a horizontal bore or passageway 19, one end of which has communication with the upper end of the bore or passageway 13 through a screen 20 while the other end of this horizontal passageway passes outwardly through the lower face of the valve plate as indicated at 21. A circular raised valve seat 22 surrounds this passageway 21 and a valve Y of light spring or 30 resilient material rests upon this seat and is held in position over it by means of a valve cover plate 35 which plate is secured to the under face of the valve plate by two screws 23.

20 By reference to Figure 6 of the drawings it will be seen that the valve Y has a circular or disc-like center portion 24 from which extend the four arms 25. The valve cover plate has in one face a circular centrally arranged cut-out portion 26 in which the disc-like portion of the valve is 35 adapted to move and from this central cut-out portion extend the radially arranged cut-out portions 27 which are adapted to receive the extending arms 25 of the valve. This valve cover plate is provided with openings 28 for the passage of the screws 23 and is additionally provided with oppositely arranged passageways 29 and 29a which are positioned in the ends of the cut-out portions or depressions 30 which communicate with the central depressed portion 26 of the valve cover 45 plate.

50 The spring arms 25 of the valve Y normally hold this valve upon its seat 22 thus closing the passageway 21.

55 The opening 29a of the valve plate cover communicates with the interior of the compressor cylinder as does also the opening 29 but the opening 29 additionally communicates with an obliquely arranged discharge passageway 31 which extends completely through the valve plate and at its upper end is surrounded by an outwardly struck circular valve seat 32 on the upper face of the valve plate.

60 A valve S which is a duplication of the valve Y in configuration and construction with the exception that it is of a lighter gauge material so as to have less resilient strength, is positioned upon the valve seat 32 and normally held thereon by its spring arms which are retained in a valve cover plate R which is a duplicate in configuration and construction of the valve cover plate Z

65 heretofore described. This valve cover plate S is secured to the upper face of the valve plate by two screws exactly as is the valve cover plate Z and has two openings 33 and 33a which communicate with the chamber 34 in the under side of the cylinder head 8.

70 A vertically arranged passageway 35 extends through the valve plate 9 and provides communication between the chamber 34 of the cylinder head and the compressor discharge passageways 10 14 and 11 to the condenser.

75 It will be immediately evident that all of the passageways in the valve plate 9 can be drilled which makes these passageways cleaner and more uniform than they are when cored in the casting. As the horizontally disposed passageway 19 is drilled from the outer peripheral edge of the valve plate the outer end of this passageway is closed by a plug 36. The valve plate can be and is preferably made of a harder and closer grained metal than the cylinder or cylinder head which provides better valve seats. The valve seats 23 and 32 extending outwardly from the valve plate as they do, they can be easily lapped when it is deemed necessary or desirable. The screen 20 positioned ahead of or in front of the inlet valve Y guards against and prevents dirt from reaching either the valves or the cylinder. The design of the complete valve assembly carried by a plate provides for easy and quick removal for inspection or repair or for the substitution of a second valve plate carrying a valve assembly in the event of any breakage.

80 The valve plate construction also makes it possible to provide a compressor of less overall height and permits the valves to be undisturbed when the cylinder head or valve plate is removed.

85 The construction, shape and design has the advantage that the number of working parts are reduced because the valve and valve spring are combined in the valve as a unit and that the seat of the valve is definitely located by the four extending arms from the valve disc. Furthermore the spring tension of the valves can be easily changed by substituting valves of a different thickness of material.

90 The valves themselves can be easily lapped in as the valve arms may be used as driving members for the valves during the lapping operation. Quiet action of the valves is assured due to the well distributed spring action.

95 The valve cover plates themselves also provide for certain advantages in that a high volumetric efficiency is had due to a small unswept compression space. Furthermore these cover plates hold the valves definitely in position on their seat and prevent their shifting and limit the valve action or movement thus prolonging the life of the valves and assuring quiet valve action. Furthermore the valve cover plates prevent any parts of the valves from dropping into the compressor cylinder and causing damage in the event that one of the valves should break. The valve cover plates for the intake and exhaust valve being identical in construction are interchangeable. The valves themselves are normally perfectly flat but the valve cover plates in the assembled construction exert an even and definite tension on each of the four legs of the valve thereby holding the valves squarely on their seats. The valves, supported as they are upon the ends of four equally spaced legs, provide a great flexibility and assure a quick action with the maximum valve lift or movement being determined by 75

the valve cover plates. The valve breakage has been found to be practically eliminated.

The construction of the valve cover plate is such as to enable the use of large area valve ports with a minimum valve lift or movement. The valve seats extending outwardly from the surface of the valve plate provide that a definite tension is exerted on the valves and seats in the assembled construction.

10 For repair or substitution of valves in the compressor it is necessary only to remove the six bolts which hold the compressor head in place, and then replace a valve plate which is complete with suction or discharge valve and then bolt the compressor head again in place. No fine nor difficult adjustment is required in the assembly of the valve plate as the correct lift and tension of the valve is automatically provided and maintained due to the design of the construction.

20 The construction of the suction and discharge shut-off valves K and L are identical and are illustrated in Fig. 5 of the drawings. Here it will be seen that the valve 40 cooperates with the seat 41. The valve is opened and closed by rotation 25 and to this end the valve stem is provided with a squared end 42 which is normally covered by a removable cap 43. The valve is locked in set position by a set-screw 44. Connection with the pipe line is had at 45 and 46.

30 Inasmuch as the inlet valve Y and its cover plate Z extend beyond the lower face of the valve plate the upper end of the cylinder is provided with a circular seat 50 for the reception of the valve cover plate. To prevent leakage a gasket 35 51 is positioned at the under side of the valve plate and a gasket 52 at the upper side thereof.

Operation

As the compressor is driven and the piston goes 40 down the gas or refrigerant is drawn through the intake or suction shut-off valve K into the passageway 10 and its communicating passageway 13. Any oil which is mixed with the gas or refrigerant separates in this passageway 13 and 45 travels downwardly into the crank case.

The gas or refrigerant itself travels upwardly 50 through the screen 20 into the horizontal passageway 19 of the valve plate and through the opening 21 to the suction valve Y. The valve Y is lifted off of its seat against spring tension thus allowing gas to pass into the cylinder above 55 the piston through the openings 29 and 29a.

When the piston has reached the bottom of its 55 stroke and the suction action has ceased the tension in the arms of the intake valve Y causes this valve to return to its seat and close. On the up-stroke of the piston the valve Y being closed gas passes upwardly through the opening 29, as its only avenue of escape, through the 60 passageway 31 in the valve plate to the escape valve R which it lifts from its seat against the spring tension of the valve arms.

With the valve R elevated and open the gas passes through the valve cover plate openings 65 33 and 33a into the cylinder head chamber 34 where it passes downwardly through the valve plate passageway 35 to the passageways 14 and 11 and through the discharge cut-off valve L to the condenser and receiver D.

70 A continued operation of the compressor is of course a repetition of the cycle of operation just described.

Having described the improved construction and having pointed out in detail its several and many advantages, what I now desire to cover and

protect by Letters Patent is defined in the following claims:

Having thus described my invention what I claim and desire to secure by Letters Patent is:

1. For use with a compressor or other like device having a cylinder and a chambered head therefor, a valve assembly comprising a plate positioned upon the cylinder beneath the chambered head, said plate having an intake passageway communicating with the cylinder, a passageway interconnecting the cylinder and the chambered head, an outlet passageway for the chambered head, a resilient valve at the under side of said plate for normally closing the inlet passageway, a resilient exhaust valve at the opposite side of said plate for normally closing communication between the cylinder and the chambered head, each of said valves comprising a disc having extending arms, valve cover plates for said valves, said cover plates having channels for receiving and guiding said valve plate arms, a chamber centrally arranged in said plates to permit movement of the disc portion of the valves, outlet passageways through said cover plates communicating with said central chamber, valve seats surrounding the ends of the passageways which said valves control, and means to secure said valve cover plates to the main plate to hold said valves against said seats under spring tension.

2. An improved compressor and valve assembly construction, comprising a compressor having a crank case, a cylinder and a chambered head therefor, a valve assembly comprising a valve plate positioned between the cylinder and its chambered head, an inlet passageway in said plate adapted for communication with the cylinder, a resilient valve for controlling said passageway, a passageway through said plate forming a communication between the cylinder and the chambered head, a resilient valve controlling said passageway, an outlet passageway in said plate communicating with the chambered head, an inlet passageway in the cylinder wall communicating with both the crank case and the inlet passageway of the valve plate, and an exhaust passageway in the cylinder wall communicating with the exhaust passageway of the valve plate, and means for securing said valves in operative positions on said plate.

3. An improved compressor or device of a similar nature, comprising a cylinder and a driven piston therefor, a chambered head for said cylinder, a valve assembly comprising a plate positioned on said cylinder beneath its chambered head, bolts for securing both said cylinder head and valve plate in position on the cylinder, an inlet passageway in said plate having its inner end communicating with said cylinder, a valve seat on said plate surrounding the inner end of said passageway, a resilient intake valve and a cover plate for holding it on said seat under resilient tension, a passageway through said plate connecting the cylinder with the chambered head, a valve seat surrounding the end of said passageway adjacent the head, a resilient valve and a plate for holding it under tension upon said valve seat, and an exhaust passageway through said plate.

4. For use with a compressor or other similar device having a cylinder and a chambered head, a valve assembly comprising a plate carrying at its opposite sides an intake and an exhaust valve, a dowel pin in the upper end of said cylinder and

a hole in said valve plate for the reception of said dowel pin to properly position said plate on the cylinder, an intake passageway in said plate communicating with the cylinder through said intake valve, an outlet passageway through said plate connecting the cylinder with the chambered head through said exhaust valve, an exhaust passageway through said plate connecting the chambered head with the atmosphere, raised 5 valve seats on said plate for said valves, said valves composed of a resilient material and comprising a disc portion seating on said valve seats and having arms extending outwardly from the opposite sides of said disc portion, valve cover 10 plates having channels for the movable reception of said valve arms and a centrally cut-out portion to permit the movement of the disc portions of the valves, means to secure said valve cover plates to the main plate to hold the valves upon 15 their seats under spring tension through pressure exerted upon the extending arms of the valve, and said cover plates having outlet openings communicating with the central depressed portion of the plates.

20 5. An improved valve assembly comprising a plate having a longitudinally disposed inlet passageway, a transversely disposed outlet passageway and a transversely arranged exhaust passageway, an inlet valve at one side of the plate 25 for controlling the inlet passageway, an exhaust valve at the opposite side of the plate for controlling the outlet passageway, a raised seat surrounding the inner end of the inlet passageway and a raised seat surrounding the outer end of 30 the outlet passageway, said inlet and outlet valves composed of a resilient material having a disc portion with extending arms, valve covers having therein channelways for the arms of said valves, means to secure said valve covers to the 35 plates for holding the valve disc portion upon the raised seat under spring tension, said valve covers being of a solid construction and having passageways therethrough and adapted for communication with the inlet and outlet passageways 40

respectively of the valve plate, the parts operating as and for the purpose described.

6. For use with a compressor having a cylinder and a removable chambered head, a unit comprising a valve assembly composed of a plate positioned between the cylinder and its head, a fluid inlet passageway in said plate communicating with a source of fluid supply and adapted for communication with the cylinder beneath the plate, a pressure discharge passageway extending through the plate and forming a means of communication between the cylinder and the cylinder head chamber, a pressure outlet passageway through said plate having communication with the cylinder head chamber and with an outlet conduit, a resilient suction operated valve at the under side of the plate for normally closing the inlet passageway to the cylinder, a resilient pressure operated valve at the opposite side of the plate for normally closing communication of the 10 discharge passageway of the plate with the cylinder head chamber, cover plates for said valves, said valves comprising a central disc portion provided with radially extending resilient arms, said valve cover plates provided with channels for 15 movably receiving and guiding said valve arms, said cover plates forming in combination with the valve plate a chamber for the valves, and said cover plates provided with openings to provide for fluid passage through the cover plates when 20 the respective valves are open.

7. An improved valve construction comprising a plate having an orifice therein, a resilient valve for normally closing said orifice, said valve comprising a disc having extending arms, a valve 25 cover plate for said disc and arms, said cover plate having a centrally arranged chamber to permit flexing movement of the disc portion of the valve and provided with channels for receiving and guiding the valve plate arms, and outlet 30 passageways in said cover plate communicating with said orifice through the central chamber of the cover plate.

LINDSAY HUGH BROWNE.
